14 Claims. (Cl. 29—203)

This invention relates to the manufacture of electric detonators and is intended to provide a novel apparatus for resistance-selecting and short-circuiting electric detonators which is designed to perform with safety and high production efficiency the steps of measuring the electric resistance of the detonator to compare the measured resistance with a specified resistance value for automatic selection of detonators and short-circuiting the wire terminals of the selected detonators either with metal foil or by stranding together and twisting the wire terminals.

In the past, in the manufacture of electric detonators, the process of selecting detonators by measurement of the resistance thereof has been performed manually by contacting the terminals of the lead wires with the terminals of a resistance meter and reading the indication of the latter or confirming a signal or the like produced. Such manual operation has often caused improper selection, for example, due to misreading of the meter indication. In addition, since for operating efficiency the measuring operation has customarily been performed with many detonators in the vicinity of the operator, some danger has always been involved that the detonators will explode when an excessive measuring current is passed through the resistance meter. In addition, the operation efficiency has been very limited as the detonators have been measured manually one by one.

Further, in the known process for short-circuiting electric detonators the wire terminals have been manually twisted or metal foil applied to the terminals by clamping, and variations in magnitude of the twisting or clamping force have been substantial and the magnitude itself has generally been limited so that the short-circuiting has often been electrically incomplete, for example, because of rust formed on the surface of the lead wires. In addition, the manual short-circuiting operation exposes the operator to the danger of explosion just as in the measuring operation.

The present invention is intended to provide a novel apparatus for resistance-selecting and short-circuiting electric detonators which is capable of mechanically performing the resistance measurement, selection and short-circuiting process included in the manufacture of electric detonators in an automatic fashion. According to the present invention, an apparatus for resistance-selecting and short-circuiting electric detonators comprises a turntable adapted to rotate intermittently, a plurality of detonator holders secured to said turntable at regular intervals along its periphery, and a number of station units arranged on an annular stationary base encircling said turntable, including a resistance-measuring unit, a reject discharging unit, a lead-wire gathering unit, a metal-foil supplying unit, a metal-foil pressing short-circuiting unit, and/or a wire-twisting short-circuiting unit, and a discharging unit for discharging finished products. The turntable is rotated intermittently with electric detonators hung on the respective holders secured to the turntable and the station units on the stationary base operate each time the turntable comes to rest in successive angular positions so that the steps of measuring resistance of detonators, dis-

2

charging faulty articles, and short-circuiting accepted articles are automatically performed. In further detail, each of the electric detonators held in the respective holders which are secured to the intermittently rotated turntable, are first measured for its resistance and are automatically sorted into two groups including acceptable and rejected articles, respectively. The rejected articles are released from the associated holders by the reject discharging unit and are discharged exteriorly of the machine. The apparatus according to the present invention is constructed so that any rejected article can never be sorted into the group of accepted articles even though the latter articles may possibly be discharged as a reject. Therefore, even if some misoperation of the machine take place, faulty articles are prevented from being transferred as acceptable to the next following station. Acceptable electric detonators thus selected are subjected to the short-circuiting process in which the terminals of the detonator wires are short-circuited either with a metal foil or by twisting together the two lead wires. For short-circuiting the lead terminals with a metal foil, the terminals of the two lead wires are first brought together by the wire-gathering unit and then are wrapped with said metal foil by the metal-foil supplying unit. Then, at the next foil pressing and short-circuiting station, the metal foil is firmly pressed against the two lead wires to electrically short-circuit the latter. For short-circuiting by wire twisting, the terminals of the two lead wires brought together are mechanically twisted together by the wire twisting unit. The detonator thus short-circuited is delivered to the following process by the discharging unit for discharging finished products. According to a further feature of the present invention, the holders on the intermittently rotating turntable as well as the station units mounted on the stationary base encircling the turntable are separated from each other by shield plates for the purpose of preventing any spread of explosion which may possibly occur during operation. By this means, even if any one of the detonators on the machine be exploded, there is no danger that the remaining detonators are involved to cause serious damage.

The present invention will now be described in further detail with reference to the accompanying drawings, which illustrate one preferred embodiment of the invention and in which:

FIG. 1 is a front elevation illustrating the inventive apparatus;

FIG. 2 is a plan view of same;

FIG. 3 is a plan view of one of the holders for holding the terminals of the lead wires of a detonator;

FIG. 4 is a side elevation of same;

FIG. 5 is a side elevation, partly in cross section, of the rejector unit for discharging faulty detonators;

FIG. 6 is a plan view of same;

FIG. 7 is a side elevation, partly in cross section, of the wire-gathering unit;

FIG. 17A is a fragmentary side elevation illustrating the manner in which the metal foil is pressed against the lead wires to short-circuit the latter; and

FIG. 18 is a plan view of an electric detonator short-circuited by the wire-twisting without use of any metal foil.

Referring to the drawings and first to FIGS. 1 and 2, which illustrate the outline of the inventive apparatus for resistance-selecting and short-circuiting electric detonators, reference numeral 1 indicates a turntable adapted to rotate intermittently by predetermined angular distances, and reference numeral 2 indicates a plurality of electric-detonator holders arranged radially on the turntable 1 at regular intervals along its periphery. The holders 2 are each constructed so as to grip at its extremity a lead wire of an electric detonator by way of electrical insulating means. A tubular structure 1A is arranged beneath the turntable 1 and about the periphery thereof for the purpose of preventing any accidental spread of explosion between the detonators and includes partition plates corresponding in number to the holders 2. Reference numeral 3 indicates a feed station for supplying detonators with lead wires to the successive holders. 3A is a stationary base encircling the turntable 1 and carries a number of station units including a cutter unit 4 for sizing the lead wires of detonators, a resistance-measuring selector unit 5, a lead-wire gathering unit 7, a wire-gathering unit 8, a metal-foil inserting unit 9, metal-foil pressing and short-circuiting unit 10, a shaping trimmer unit 11, a wire-twisting short-circuiting unit 12 and a discharging unit 13 for discharging finished articles. Reference numeral 6 indicates a reject discharging unit provided beneath the turntable for discharging rejected articles; and reference numeral 14 indicates a central stationary supporting base carrying a lead-wire opening device 15 and a metal-foil clamping device 16.

Referring next to FIGS. 3 and 4, which represent a plan and a side view, respectively, of one of the holders indicated at 2 in FIG. 2, reference numerals 17 and 18 indicate respective clamping arms with insulation adapted to be pressed against the opposite sides of a central insulator 19. These arms cooperate to grip the base terminals of the two lead wires of a detonator separately between the arm 17 and insulator 19 and between insulators 18 and insulator 19. Reference numeral 30 indicates a cam for opening and closing the clamping arms 17 and 18.

Reference will next be made to FIGS. 5 and 6, which illustrate the structure of the reject discharging device 6 shown in FIG. 1. A support bracket 20 is secured to a plate 21 arranged beneath the turntable 1. 22 is a movable rod mounted on the bracket 20 for vertical movement. The vertically movable rod 22 has a cam 22A at the top end in engagement with another cam 30 for opening and closing said holder 2 and has a lug 22B in its central portion for engagement with a depressor lever 28. A cam roller 23 is secured to the another end of vertical rod 22 for cooperation with a cam 24 provided to actuate the rod 22 upwardly. The cam 24 is designed to be rotated through a gear means in synchronism with the rotation of the turntable 1. A coil spring 25 is arranged to normally bias the vertical rod 22 to its upper position. A steel ball 26 is arranged for keeping the vertical rod 22 in a predetermined position and is normally biased against the rod 22 by a coil spring 27. The depressor lever 28 is actuated by an electromagnet 29 which is accommodated in a casing formed of an insulating material and through which the depressor lever 28 extends. The electromagnet 29 is mounted on the plate 21 and is operable upon reception of an indication from the resistance-measuring selector unit 5 that the detonator supplied is acceptable.

In FIG. 7, which illustrates the wire-gathering unit in-

5 indicated at 8 in FIGURE 2 for bringing together the lead wires, reference numeral 31 indicates a support frame secured to the stationary base 3A arranged about the turntable 1. 32 is a vertical slide rod operable to slide with cam means through guide apertures 37 and 38 provided at the top and bottom of support frame 31. A rotary wire-gathering tube 34 is mounted on a bracket arm 33 by way of a ball bearing incorporated therein. The bracket arm 33 is secured to said vertical rod 32 for vertical movement therewith. A shaft 35 has formed thereon a lug for engagement with the wire-gathering tube 34 to impart rotation thereto and the shaft 35 carries a belt pulley 36. The wire-gathering tube 34 has at its bottom a conical recess formed with an aperture and a slit designed in conformity with the lead wires of the electric detonator to gather the wires.

Reference will next be made to FIGS. 8 and 9, which represent a front and a side view, respectively, of the metal-foil supplying unit shown in FIG. 2. Reference numeral 39 indicates a support bracket secured to the stationary base 3A arranged to encircle the turntable 1; 40 indicates a supply reel of metal foil for short-circuiting the lead wires of electric detonators; 41 indicates a feed roller for feeding a predetermined length of metal foil, and the roller 41 has a slot to prevent slippage of the foil; 42 indicates a foil presser roller arranged for contacting engagement with feed roller 41; and 43 indicates a ratchet wheel for imparting intermittent rotation to the feed roller 41 by way of gearing. A vertically movable rod 44 has a pawl 45 pivotally secured thereto by a pin 46 and the rod 44 slides through the guide apertures provided at the top and bottom of the support bracket 39 to rotate intermittently the ratchet wheel 43 in engagement with pawl 45. A metal-foil inserting rod 48 is secured to the vertical rod 44 by way of a mounting plate 47 for vertical movement with the rod 44. A cutter blade 49 is arranged to slide in a groove formed in the support bracket 39. A coil spring 50 is provided to bias the cutter blade 49 and a resilient plate 51 is provided to hold the blade 49. A ledge blade 52 is arranged to cooperate with the cutter blade 49 to cut the metal-foil strip 40 to a predetermined length. A vertical rod 53 is formed adjacent to one end with a rack and is guided for vertical sliding movement by the support bracket 39. A pinion 54, meshing with the rack on the vertical rod 53, is rotatable through an angle of 90 degrees. A metal-foil grip finger 55 is secured to a shaft 56, which carries said pinion 54, and is rotatable with the latter. The grip finger 55 is composed by a pair of leaf springs to receive and resiliently hold the metal-foil which is V-formed.

In FIGS. 10 and 11, which illustrate the metal-foil clamping device indicated at 16 in FIG. 2, reference numeral 57 indicates a base frame arranged on the stationary base 14 shown in FIG. 2; 58 indicates a slider base carrying a roller 72 and slidable back and forth in a groove formed in the base frame 57 under control of a cam 59. A slider rod 60 carries a wedge-formed cam 66 at its extremity and a roller 71 at the other end and slides through an aperture 58A formed in the slider base 58 for back and forth sliding movement under control of a cam 61.

A spring 70 is secured at one end to the slide rod 60 by an anchor 73 to normally urge the slide rod 60 rearwardly. A pair of clamp levers 64 and 65 are pivoted at 62 and 63, respectively, to the slider base 58 and operable upon insertion of the wedge-formed cam 66 to clamp metal-foil grip finger 55, shown in FIG. 8. A spring 67 is provided to normally keep the clamp levers 64 and 65 in open position. A lead-wire presser plate 68 is arranged to receive the terminals of the lead wires of a detonator and is operable to force the terminals into the V-shaped space defined by the metal-foil as held in the metal-foil grip finger 55 when the slider base 58 is advanced. A spring 69 is provided to normally hold the slider base 58 in its retracted position.

In FIG. 12, which illustrates the metal-foil pressing short-circuiting unit indicated at 10 in FIG. 2, reference numeral 80 indicates a support bracket secured to the stationary base 3A encircling the turntable 1 (FIG. 2); and 81 indicates a pressure-supporting rod formed at the forward end with a groove for accommodating a ledger blade 85 (of angular or flat form) and carries at the other end a roller 90 to cooperate with a cam 93. The pressure-supporting rod 81 is movable back and forth through a guide aperture formed in the support bracket 80 under control of cam 93. A pressure rod 82 is slideable back and forth through a groove formed in the top portion of the support bracket 80 under control of cam 91. Another pressure-supporting rod 83 carries at its extremity a ledger blade 85 and is guided by an aperture formed in the support bracket for back and forth movement under control of a cam 92. A presser blade 84 is of angular or flat form and is arranged to oppose the ledger or blade 85. A spring 86 is provided to adjust the force acting upon the presser blade 84 and is adjustable by a retainer nut 87. Springs 88 and 89 serve to normally keep said pressure-supporting rods 81 and 83 in their respective retracted positions and a cam 94 serves to forcibly retain the pressure-supporting rod 81 in its retracted position.

In FIG. 13, which illustrates in cross section the wire-twisting short-circuiting unit indicated at 12 in FIG. 2, a support bracket 100 is secured to the base 3A arranged about the turntable 1 shown in FIG. 2. A vertically movable tubular rod 101 has at its top an integral overhanging arm formed with a circular recess, in which a ball bearing 104 is arranged. The tubular rod 101 carries at its bottom a cam follower roller 102 which cooperates with a cam 103 to move the rod 101 vertically through a vertical bore formed in said support bracket 100. A rotative shaft 105 carries a belt pulley 107 at its top with a friction wheel 106 mounted at the bottom of the shaft 105 in contacting engagement with the periphery of the cam 103 on one side thereof to rotate the shaft 105, which is fitted in the axial bore of the tubular rod 101. A shaft 109 is journaled in the ball bearing 104, mounted in the overhanging arm of the tubular rod 101 and carries at the top a belt pulley 108, which is connected by a belting with pulley 107. A pair of grip fingers 110 and 111 are secured by leaf springs 112 and 113 respectively to the bottom of the shaft 109 for the purpose of gripping the wire terminals of a detonator. Leaf springs 112 and 113 serve to keep the grip fingers 110 and 111 open. A ball bearing 114 is provided to close the grip fingers when they descend while rotating and the bearing 114 is fitted in a circular recess formed in a portion of the support bracket 100. A tension spring 115 is provided to urge the tubular rod 101 to descend and the spring normally holds the roller 102 carried by the tubular rod 101 in contact with the cam 103.

Reference will next be made to FIGS. 14 and 15, which illustrate the structure of the discharging unit 13 (FIG. 2) for discharging finished articles. Reference numeral 120 indicates a support arm secured to the base 3A, which is arranged to encircle the turntable 1 as shown in FIG. 2. Seamless belts 121 and 122 are provided to carry electric detonators by gripping the lead wires of the latter and are driven by respective pulleys 123 and 124 in the same direction. Gear wheels 132 and 133 are mounted on respective shafts 135 and 136 and a pulley 125 is arranged to impart rotation to the gear 132 by way of pulleys 126 and 127. Pulleys 128 and 129 are arranged to support the belts 121 and 122 at their ends remote from gear wheels 132 and 133. Tension rods 130 and 131 are provided to carry the respective pulleys 128 and 129 and they are biased by springs 137 and 138 in a direction to tension the respective belts 121 and 122.

Guide plates 139 and 149 are provided to obtain a satisfactory contacting pressure between the running belts. Idlers 134 are arranged to guide the returning runs of the belts.

Reference will next be made to FIGS. 16, 17 and 18, in which like references indicate like parts. Referring first to FIG. 16, reference numeral 141 indicates an electric detonator with lead wires 142; having their naked terminals 143 which have not been short-circuited yet. In FIG. 17, a metal foil 144 is shown embracing the naked terminals 143 of the lead wires 142. In FIG. 17A, the metal-foil 144 is shown clamped into corrugated form to short-circuit the lead wires. In FIG. 18, reference numeral 147 indicates the naked terminals 143 of the two lead wires 142, which are shown twisted and short-circuited to each other without use of any metal-foil such as shown at 144 in FIG. 17.

The apparatus for resistance-selecting and short-circuiting electric detonators operates as will be described hereinafter to automatically measure the resistance of electric detonators for selecting acceptable ones and to short-circuit the terminals of the lead wires of the selected detonators.

The operation of the apparatus will now be described in detail.

Electric detonators 141 to be short-circuited, such as shown in FIG. 16, are fed into the apparatus at the feed station 3 (FIG. 2) by the operator to be held by the successive holders 2, secured to the turntable 1, with the naked terminal portions of the detonator wires 142 held in the holders, and are carried in a circular path as the turntable 1 is rotated intermittently. During this rotation, the naked terminal portions 143 of the lead wires 142 of each detonator are gripped by the clamping insulators 17 and 18 with central insulator 19 interposed between the terminal portions 143 for insulating the latter from each other. The electric detonator clamped in this manner is first brought opposite to the sizing trimmer unit 4 (FIG. 2) where the naked terminal portions 143 of the lead wires 142 are cut to size.

Subsequently, the detonator is brought opposite to the lead opening unit 15, mounted on the central stationary base 14, and the naked terminal portions of the two lead wires 142 are opened by the device 15 to prevent contact between the two lead wires 142. Then, at the resistance-measuring selecting station 5, the detonators are measured for resistance to compare with the specified resistance value and thus only acceptable articles are electrically selected to be short-circuited. Faulty articles are removed by the reject discharging unit 6 (FIG. 1). The resistance-measuring selector unit 5 is constructed to measure the detonator resistance and, only when the detonator has proven to be acceptable does it send an electric signal to the electromagnet 29 of the reject discharging unit 6 so that the electromagnet 29 is actuated to force down the depressor rod 28 and hence the vertical rod 22. At this time the steel ball 26 is fitted into a recess formed in the adjacent portion of the vertical rod 22 under the bias of spring 27 to keep the vertical rod 22 in its depressed position. Simultaneously, cam 22A mounted on top of the vertical rod 22 is lowered apart from the cam 30, provided for opening and closing the holders 2 to allow the latter to proceed to the next station with the clamping arms 17 and 18 of the holder remaining in closed position. If a faulty detonator is detected, no electrical signal is transmitted from the resistance-measuring selector unit 5 to the electromagnet 29, and thus the electromagnet 29 of the reject discharging unit 6 remains inoperative. Therefore, the vertical rod 22 maintains its upper position under the bias of spring 25 while the cam 30 for operating the holders 2 is in contact with the cam 22A mounted on top of the vertical rod 22 and, rotating with the turntable 1 acts to open the clamping arms 17 and 18 so that the faulty article previously held in the holder 2 is released to fall and thus can never be forwarded to the next station. It is noted that the spring 25, acting at all times to bias the vertical rod 22 to its upper position, not only serves in normal operation to eject any faulty article but also is effective

to prevent such faulty detonator from being transferred to the next following station as an accepted article even in the case of misoperation or any other trouble as in the measuring instrument or the electromagnet. In other words, in cases where the measuring instrument or other element is inoperative, the reject discharging unit 6 operates to eject all acceptable articles in the same manner as in its normal operation ejecting faulty ones. Therefore, with this reject discharging unit 6, any faulty article can never be transferred to the next station through some acceptable articles may be rejected as faulty ones.

The electric detonator selected in the manner described above is subsequently subjected to the short-circuiting process in which a metal-foil is employed or the lead wires are twisted to short-circuit the latter. In the event that a metal-foil is used, the selected detonator 141 being carried by the intermittently rotating turntable 1 comes to rest immediately beneath the wire-gathering units 7 and 8 (FIG. 2) and the lead wires are brought together so that a metal foil may readily be inserted in the next following station. In other words, the terminal portions 143 of the lead wires 142 are preliminarily brought together by the lead-gathering unit 7 and then carried to be positioned immediately below the next wire-gathering unit 8. While the electric detonator has come to rest just beneath the wire-gathering unit 8, the vertically movable rod 32 (FIG. 7) is actuated to descend and at the same time the rotary wire-gathering tube 34 is lowered while rotating about its own axis. As the result, the terminal portions 143 of the lead wires 142 are collected by the conical recess formed at the bottom of the wire-gathering tube 34 toward its axis of rotation and are partly guided into the aperture formed in the apex of the conical recess to be twisted. Subsequently, the vertical rod 32 is raised to complete the lead gathering operation. On this occasion, rotation of the wire-gathering tube 34 is caused by means of the pulley 36 mounted on top of the shaft 35 and a keyway formed in the wire-gathering tube to cooperate with a projecting key formed in the top portion of the shaft 35 and slideable in said keyway.

The electric detonator with its lead wires brought together is then rotated until it is positioned opposite to the metal-foil supplying unit 9 (FIG. 2). When the electric detonator comes to stop at this station, the vertically movable rod 44 (FIG. 9) is operated from the drive mechanism to rise. Accordingly, the pawl 45 pivoted at 46 to the rod 44 drives the ratchet wheel 43 by a predetermined angular distance thereby to rotate the feed roller 41, which cooperates with the presser roller 42 to draw the metal-foil strip from the supply reel 48 by a predetermined length as indicated by the arrow in FIG. 9. When the vertical rod 44 completes its foil-feeding motion in its uppermost position, the foil cutter blade 49 (FIG. 8) is subjected to the downward bias of the resilient plate 51 and spring 50 now stressed by the rise of the foil inserting rod 48. Subsequently, as the vertical rod 44 starts to descend, the cutter blade 49 is lowered in advance of the descent of the foil inserting rod 48, which is secured to the rod 44 by way of the mounting plate 47, and cooperating with the ledger blade 52 cuts the metal-foil to a predetermined length. Thereafter, the foil inserting rod 48 descends to shape the metal-foil cut to length into V-form by cooperation of the T-shaped extremity of the foil inserting rod 48 with the rounded open slot formed in the adjacent portion of the support bracket 39 and the rod 48 delivers the metal-foil so shaped into the metal-foil grip finger 55. Immediately thereafter, the metal-foil inserting rod 48 is raised from the grip finger 55. The grip finger 55 now holding the V-shaped metal-foil is tilted forwardly by an angle of 90° as indicated by the arrow in FIG. 9 with rotation of the pinion 54, carried on the shaft of the grip finger, to embrace the lead terminals 143 with the V-shaped metal-foil carried by the grip finger. On this occasion, the 90° rotation of the pinion gear 54 is produced by the corresponding rise of the vertical rod 53,

which carries a rack meshing with the pinion 54. Subsequently, metal-foil clamping device 16 (FIG. 2) is operated to force the lead terminals 143 into the V-shaped metal-foil while at the same time pinching the latter to ensure its engagement with the lead terminals 143. To this end, the slider base 58 (FIGS. 10 and 11) is advanced by cam 59 into a position to close the metal-foil gripping finger 55 so that the lead presser plate 63 forces the lead terminals 143 into the V-shaped metal-foil held in the grip finger 55. Subsequently, the slide rod 60 is advanced beyond the advanced position of the slider base 58 to wedge the pointed extremity of the wedge cam 65 in between the clamp levers 64 and 65 so that the V-shaped metal-foil is lightly clamped together with the grip finger 55. In this manner, the lead terminals 143 of the electric detonator are held lightly clamped with the metal foil 144 as shown in FIG. 17. Upon completion of the above operation, the parts of the machine are restored to their normal position.

Subsequently, the electric detonator with its lead terminals 143 clamped with metal-foil 144 is carried further to be positioned opposite to the metal-foil pressing and short-circuiting unit 10 (FIG. 2). Pressure-supporting rods 81 and 83 (FIG. 12) extending through the respective guide apertures in the support bracket 80 are now forced to slide therein by rotation of respective cams 92 and 93, and thus positioned so as to receive the lead terminals 143 clamped with metal-foil 144 in the slot formed in the forward end of the rod and accommodating ledger blade 85. Subsequently, the presser rod 82 mounted on top of the support bracket 80 is advanced by rotation of cam 91 to cooperate with the ledger blade 85, carried on the extremity of the pressure supporting rod 83, so that the lead terminals 143 are pressed together with the metal-foil 144 into corrugated form as indicated at 145 in FIG. 17A. On this occasion, the pressure or clamping intensity can be freely adjusted by selecting the spring rate of the biasing spring 86 and adjusting the retainer nut 87 to obtain a clamped joint satisfactory for the electrical short-circuiting of the detonator wires. Upon completion of the clamping operation, presser rod 82 and pressure-supporting rods 81 and 83 are returned under control of the respective cams 91 and 94 and springs 88 and 89. Namely, first the presser rod 82 is retracted under control of cam 91 and then pressure-supporting rod 81 is forced back by spring 88 and cam 94. Finally, pressure-supporting rod 83 is retracted under the bias of spring 89 to complete the metal-foil pressing and short-circuiting operation. The retraction of the pressure supporting rod 83 delayed behind the retraction of the pressure-supporting rod 81 is to facilitate the disengagement of the clamped lead terminals from the slot in the extremity of the pressure-supporting rod 81. Now that the lead short-circuiting operation employing metal-foil has been completed, the electric detonator is transferred to the shaping trimmer unit 11 (FIG. 2), where it is trimmed to remove any possible irregularities such as in length of the lead wires and in position of the short-circuiting foil. Finally, the detonator is delivered as an acceptable article to the next process by the product discharging unit 13 (FIG. 2).

For short-circuiting by wire twisting, the lead wires are preliminarily brought together by the wire gathering units 7 and 8 (FIG. 2) just as with the case of the short-circuiting operation employing metal-foil. However, in this case, the metal-foil inserting unit 9, metal-foil pressing and short-circuiting unit 10 and the shaping trimmer unit 11 are held inoperative, the detonator holders 2 being carried by intermittent rotation of the turntable 1 past these station units to be first positioned opposite to the wire-twisting short-circuiting unit 12, where the lead terminals 143 of the detonator are twisted together to be short-circuited as indicated at 147 in FIG. 18. That is, when the detonator with its lead wires brought together is positioned opposite to the wire-twisting short-

circuiting unit 12, the vertical tubular rod 101 slidably supported in the bracket 100 (FIG. 13) is lowered under the bias of tension spring 115 with rotation of cam 103.

At the same time, the pair of grip fingers 110 and 111, provided at the overhanging top portion of the vertical rods 101 and 113 are actuated to close their bottom extremities toward each other because of the tapered form of the grip fingers themselves engaging the inner periphery of the inner race of the ball bearing 114 so that the lead terminals 143 of the electric detonator positioned immediately beneath the grip fingers are gripped between the extremities thereof now closed. At this time, the shaft 105 extending through the vertical tubular rod 101 is rotated by the frictional engagement of the friction wheel 106 mounted on the bottom of the shaft 105 with the side of rotating cam 103. The rotation of the shaft 105 is transmitted to the shaft 109 through the medium of the pulley 107 on top of shaft 105, pulley 108 on top of the shaft 109 and the belting interconnecting the two pulleys. By this means, the grip fingers 110 and 111 carried on the bottom of shaft 109 are rotated a predetermined number of times carrying the electric detonator with its lead terminals 143 held between the grip fingers. As a result, the lead terminals are twisted together and short-circuited as indicated at 147 in FIG. 18. Upon completion of the short-circuiting operation, the tubular rod 101 is raised by the cam 103 to allow the grip fingers 110 and 111 to be restored to their open position under the bias of the leaf springs 112 and 113 thereby to release the now short-circuited lead terminals.

The electric detonator thus short-circuited with a metal-foil or by the twisting of the lead wires is delivered to the discharging unit 13 (FIG. 2) and discharged as a finished product onto an appropriate conveyor. Referring to FIG. 14, which illustrates the discharging unit, the belts 121 and 122 are entrained about pulleys 123, 128 and 124, 129, respectively and are continuously driven so that the adjoining portions of the two belts 121 and 122 are moved in the discharging direction. The belt drive includes a pair of meshing gears 132 and 133 mounted on respective shafts 135 and 136 carrying driving pulleys 123 and 124, respectively, and pulleys 125, 126 and 127 connected by a belting with a drive shaft, pulley 125 being secured to the shaft 135. The electric detonator being carried by one of the holders 2 mounted on the rotating turntable 1 is brought opposite to the joining region of the continuously running belts 121 and 122. At this time, the holder 2 is released under control of the cam below and the lead terminals 143 of the electric detonator released from the holder 2 are inserted between the adjoining portions of the belts 121 and 122 so that the detonator is suspended therefrom and delivered out for the next operation.

With the construction and arrangement described, it will be appreciated that the apparatus of the present invention has various advantageous features as described below. First, since the resistance measurement of electric detonators, rejection of faulty detonators and short-circuiting of accepted detonators are all carried out mechanically in an automatic fashion, the danger previously involved in manual operation has been eliminated. Secondly, there is no possibility in selecting detonators that any faulty article be delivered to the following station as an accepted article because of misreading of the indication or misoperation possibly occurring in the conventional manual procedure and the quality of all finished products can thus be fully guaranteed. A further advantage is that the short-circuiting can be effected with electrical perfection since the short-circuited joints are formed positively and uniformly by mechanical means. Particularly, it will be noted that the present invention is highly valuable in the industry as it has completely mechanized all the operations concerned, ensuring the safety in the manufacture of electric

detonators while substantially improving the production efficiency.

What I claim is:

1. An apparatus for handling electrical detonators to measure their electrical resistance, to reject detonators whose resistance values are unacceptable and to short circuit acceptable detonators, said apparatus comprising an intermittently rotatable turntable, a plurality of holders peripherally mounted on said turntable for releasably engaging respective detonators, said detonators having lead wires with free ends, means for measuring the electrical resistance of the detonators in said holders when the turntable is intermittently halted, a discharge device for detonators operable upon reception of a signal from the electrical resistance measuring means to release a rejected detonator from a holder when said signal is absent, a metal foil supplying means for severing a length of foil from a supply thereof and forming said length into V-shape when the turntable is in rotation, said foil supplying means feeding a V-shaped foil to the end portions of the lead wires of said detonator when the turntable is halted and means for securing the foil to the ends of the lead wires of a detonator by clamping the foil and the ends of the lead wires.
2. An apparatus according to claim 1 wherein each holder is openable and closable and includes a cam for opening and closing said holder.
3. An apparatus according to claim 2 wherein the discharging device comprises a vertically movable rod including a second cam at the upper end of the rod for contacting the first said cam for opening the holder, means for retaining said rod in such position that said second cam contacts said first cam, means depressing said rod to a position in which said second cam is out of contact with said first cam when a signal is received from the electrical resistance measuring means, means retaining said rod at the depressed position until said holder has passed to the next position, and means releasing said retaining means to return said rod to the original position before the arrival of the next successive holder.
4. An apparatus according to claim 3 wherein the means depressing the vertically movable rod comprises a lever for depressing the rod, and an electromagnet for operating said lever, said electromagnet being adapted for receiving signals from the resistance measuring means and operable only when an acceptable detonator is detected.
5. An apparatus according to claim 1 wherein the means of supplying the metal foil comprises a metal foil holding means turnable by 90 degrees to supply the V-shaped metal foil to the ends of the lead wire of the detonator, means for feeding a metal foil of constant length when said turntable is rotating, a first vertical movable rod having means for severing said metal foil and depositing the severed foil into said holding means to form said severed foil into a V-shape, and a second vertically movable rod turning said holding means by an angle of 90 degree in the upward movement thereof and returning said holding means to replace to the original position in the downward movement thereof when the turn-table is halted.
6. An apparatus according to claim 5 wherein said metal foil holding means include two spring plates.
7. An apparatus according to claim 5 wherein said means for feeding the metal foil comprises two rolls rotatable in contact with each other and between which the metal foil is clamped and means for driving said rolls in rotation.
8. An apparatus according to claim 5 wherein the first rod includes a pawl, a gear being provided for driving the foil feeding means, said pawl engaging said gear in the upward stroke of said first rod and rotating said gear by a constant angle, the first rod further including a depressing rod with a cutting edge constituting the means for severing the foil and depositing the same into the holding means.

9. An apparatus according to claim 5 wherein the second rod is provided with a linear tooth for engaging with a gear driving the holding means.

10. An apparatus according to claim 1 wherein the means for securing the metal foil piece to the lead wires of the detonator comprises a sliding base having clamping arms on the end thereof and a sliding rod having a wedge-shaped cam on the end of said sliding base.

11. An apparatus according to claim 10 comprising cam means for forwardly driving the sliding base and the sliding rod when the turntable is halted.

12. An apparatus according to claim 1 wherein the means for securing the metal foil to the lead wires of the detonator comprises a first sliding rod having a guide groove on the end thereof, a second sliding rod having a

receiving die on the end thereof and a third sliding rod having a pressing die opposite said receiving die.

13. An apparatus according to claim 12 wherein said first, second and third sliding dies are driven by cams.

14. An apparatus according to claim 12 comprising a spring mounting said pressing die on said third sliding rod.

CERTIFICATE OF CORRECTION

Patent No. 3,383,753

May 21, 1968

Satoshi Watanabe

It is certified that error appears in the above identified patent and that said Letters Patent are hereby corrected as shown below:

In the heading to the printed specification, line 8, "Aug. 5, 1964" should read -- Aug. 6, 1964 --.

Signed and sealed this 16th day of December 1969.
